UNITED STATES PATENT OFFICE.

WALTER M. DAKE, OF DENVER, COLORADO, ASSIGNOR OF ONE-HALF TO
MILTON O. WATERBURY, OF DENVER, COLORADO.

DESIGN FOR A STICK-PIN.

No. 38,174.

Specification for Design.

Patented Aug. 21, 1906.

Application filed June 29, 1906. Serial No. 324,070. Term of patent 3½ years.

To all whom it may concern:

Be it known that I, WALTER M. DAKE, a citizen of the United States, residing in the city and county of Denver and State of Colorado, have invented a new, original, and ornamental Design for a Stick-Pin, reference being had to the accompanying drawing, which forms a part of this specification.

This invention relates to a new, original, and ornamental design for a stick-pin, the

said design being illustrated in the accompanying drawing.

What I claim is—

The ornamental design for a stick-pin, as shown.

WALTER M. DAKE.
